UNITED STATES PATENT OFFICE

RICHARD HENSEL AND EWALD SAUSMIKAT, OF HOBOKEN, NEW JERSEY

ILLUMINATED HOUSE NUMBER

Application filed February 5, 1929. Serial No. 337,546.

The main object of this invention is to provide a continually illuminated number which may be seen and distinguished at a distance. The house numbers now in use are not readily distinguished at night, especially in suburban districts, and to eliminate this difficulty I propose to use a filler of radium substance encased in a form having the shape of the number which it is to represent.

10 Another object of this invention is to provide means for hanging these house numbers in a convenient manner so that the same may be supported from a strap, plate or the like.

The above and other objects will become 15 apparent in the description of the invention, in which characters of reference refer to like-named parts in the drawing.

Referring briefly to the drawing, Figure 1 is a front elevational view of one of the 20 house numbers.

Figure 2 is a sectional elevational view of the same, showing means for suspending house numbers from a strap or the like.

Figure 3 is an enlarged elevational view 25 of a portion of the house numbers, showing the means for adjusting the securing member.

Figure 4 is an application of the principle to a train indicating means.

Referring in detail to the drawing, the 30 numeral 10 indicates the wall of a dished-out form which has a back 11. This dished-out member, of a shape similar to the number it is desired to represent, is filled with a radium-treated substance 13 which gives off 35 light emanations, as is well-known. The back 12 of the number is provided with a plurality of ridges 14 which are engaged by a member 15 having similar ridge surfaces. This member 15 is provided with a hook 16 at its lower 40 end. The form is also provided with an upper hook 16^a, and between these two hook members a plate, forming part of the mounting member, is secured. The head 17 of a plunger is movable in a casing 18 and the 45 plunger, forming part of the head, has a spring 20 mounted thereon which urges the head to seat upon the top of the cartridge 18. This cartridge is provided with threads 19 which are tapped into the back 12 of the house 50 number. The cartridge is positioned in a

slot 20^a which forms part of member 15. In Figure 4 a modified application of a visible indicator is shown. This visible indicator is adapted to be used in train sheds or under similar conditions and comprises a frame 21 which surrounds a glass plate or similar other material upon which a hand 23 is engraved, and beneath this hand words, such as "Trains" is also engraved.

It is to be noted that certain changes in 60 form and construction may be made without departing from the spirit and scope of the invention.

We claim:

1. A device of the class described comprising a dished-out form, said dished-out form being adapted to be filled with some light-emanating substance, a rigid hook on said form, a movable hook on said form, said hooks being adapted to permit mounting of said device to a strap or the like, ridges arranged on said form, and means engaging said ridges for adjustably shifting said movable hook member to any desired position.

2. A device of the class described comprising a dished-out form, said dished-out form being adapted to be filled with some light-emanating substance, a rigid hook on said form, a movable hook on said form, said hooks being adapted to permit mounting of said device to a strap or the like, ridges arranged on said form, a cartridge mounted on said form, said movable hook member having a slot therein receiving said cartridge, and movable means in said cartridge adjusting said movable hook to any position along the ridges thereof.

In testimony whereof we affix our signatures.

RICHARD HENSEL. 90
EWALD SAUSMIKAT.
